UNITED STATES PATENT OFFICE.

FRANKLIN HALE CALL, OF PORTLAND, OREGON.

CABINET FOR PHONOGRAPHIC RECORDS.

Specification of Letters Patent.

Patented Jan. 6, 1920.

1,327,143.

Application filed May 29, 1919. Serial No. 300,612.

To all whom it may concern:

Be it known that I, FRANKLIN HALE CALL, a citizen of the United States, residing at Portland, in the county of Multnomah and State of Oregon, have invented a new and useful Improvement in Cabinets for Phonographic Records, of which the following is a specification, reference being had to the accompanying drawings.

10 My invention relates to cabinets as a class.

The object of my invention is to provide a cabinet or case wherein a desired number of phonographic records of common type may be deposited and secured therein in such a manner that only one at a time may be removed or re-placed. This object, as well as other advantages, I attain by the construction, combination and arrangement of parts illustrated in the accompanying drawings which form a part hereof.

Figure 1 is a plan view of the device with the top case cover removed.

Fig. 2 is a front elevation with parts of case broken away.

25 Fig. 3 is a vertical sectional view showing the mechanism applied to a single record in place.

Fig. 4 is a like view showing position of the mechanism with a record projected for removal.

Fig. 5 is a view of parts of the mechanism in connection with an empty carton.

Fig. 6 is a detail plan view of the ends of the lock strap secured in place.

35 Fig. 7 is a detail front view of the same.

Fig. 8 is a sectional view on the line 8--8 of Fig. 2.

Like numerals refer to like parts in the views.

40 A cabinet or case 9 of convenient form is provided. Upon the upper surface of the case bottom oppositely disposed brackets 10 are secured. A horizontal rod 11 is secured in the brackets transversely of the bottom

45 and at a desired height therefrom. A series of cartons 12, of desired form, are pivoted in their lower parts upon the rod 11. The cartons are provided with metal reinforcing plates 13 where pivoted, and similar plates

50 14 upon their outward ends, also a carton spreader plate 16. The plate 14 is angled to extend in front of the carton and upon this part of the plate numbers of records may be placed as shown in Figs. 1 and 2. A coil

55 spring 15 is placed upon the rod 11 between

the outermost carton and its opposing bracket 10, in a manner to retain the cartons in vertical position. Within the carton and the reinforcing plate 13 a rigid seat 16' is secured in a position to receive the lower 60 lever arm. In the rear of the case two oppositely disposed brackets 17 are secured upon the upper surface of the bottom. A horizontal rod 18 is secured in these brackets transversely of the bottom and at a desired 65 height therefrom. Opposite each carton a bell crank lever 19 is pivoted at its angle upon the rod 18. The lower arm of the lever 19 extends a short distance within its opposing carton and over the seat 16', so 70 that it may rest thereon. The lower arm is grooved in its upper part a desired distance rearward from its free end. A spring 20 is secured upon the upper surface of the case bottom and below said lower arm, in position to engage the lower edge thereof. The upper arm of the lever 19 has an integral angled member 21 of desired form. The lever 19 has a swelled part 22 at its angle to provide a weight beyond the fulcrum bar 75 18. A thin arm 23 is rigidly secured in its upper part upon the rear part of the carton. The arm 23 extends downwardly and has a curved longitudinal opening 24 therein. Along the upper edge of this opening the 80 horizontal part of the member 21 extends through the opening 24 of the arm 23 and its upward part engages the side of the arm 23.

In the forward part of the case is a transverse groove 26 in the upper part of the bottom. Guides 27 are secured upon the bottom along said groove. A vertical, forked standard 28 is provided. It has a base plate 29 slidable over the upper surface of the 90 guides with grooves in its lower sides, within which the edges of the opposing guides may pass. Upon the lower part of the standard base plate 29 a lock finger 30 is rigidly secured and extends longitudinally 95 in the groove 26. It has a notch 31 in one side near its free end. A yoke spring 32 is secured at one of its ends to the case bottom by screws 33. Its free end extends downward beyond the end of one of the guides 100 and into the groove 26. This end is positioned so that it will enter the groove 31 of the lock finger 30 when the same is opposite the spring 32. A key opening 34 extends through the front of the case arranged so 105

110

that a key will pass through it transversely of the slot and its end engage the spring 32 and the key will also move on a horizontal plane below that of the travel of the lock finger 30. A key 35, of desired form, is provided, having a slot 36 in its side near the end. Upon the interior of said walls of the case are vertical opposing guides 37. A thin metal strap 38 passes through the guides 37 and the slot 26, the opposing ends of the strap 38 extending over the respective upper ends of the forked standard 28 and being rigidly secured to the same by riveted extensions 39. The forward end of the cartons and plates 14 are provided with slots 40, arranged and formed to allow the upper ends of the standard 28 to pass through them, also to allow the strap 38 to pass through the slot and retain the forward end 20 of the carton from rising or lowering, when the carton is on either side of the standard, and to allow the carton end to move when it has passed from the strap to a position within the standard fork.

25 To the rear of the carton slot 40 is a second slot 41, into which the lower part of the standard may pass to allow the outer end of the carton to descend completely. Upon one of the guides 37 opposite the key opening 34 a spring 42 is secured. This spring extends downward into the groove 26 and opposite the notch 36 of the key 35, when it is inserted, and engages the key in this slot. It also extends far enough to be engaged by 35 the end of the lock finger 30 when it is moved forward below the key 35. A record 43 is shown within a carton.

It will now be seen that when the carton 12 is lowered, as shown in Fig. 4, the member 21 of the upper arm of the lever 19 engages the carton arm 23 in its lowest slot 25, and the forward end of the carton is free from the strap 38, and rests within the forks of the standard 28. In this position 45 the carton is locked so that it cannot be raised. The other cartons are also locked so that they cannot be moved forward. The record 43 can then be removed from its position as shown in Fig. 4. To lock a carton with a 50 record therein, the record is inserted in the carton in its position in Fig. 4 and the record pressed rearwardly. It then engages the lever 19 in its grooved arm and depresses this arm. This movement releases the upper lever arm from engagement with one 55 of the lower notches 25 and its member 21 passing upwardly through the opening 24 of the carton arm 23, allows this arm to descend. The standard 28 is then moved to 60 bring its fork opposite another carton and the strap 38 passes through the carton slot 40 and the first carton is thus locked, and a record cannot be removed from it through the space between the upper end of the 65 standard 28 and the top of the case. The

spring 20 and lever weight 22 are provided to retain the lever in the position shown in Fig. 4.

The device may be operated with or without the key mechanism, as already described. The key mechanism, however, is a useful feature of my device. It will be seen that when the key is inserted, it presses the spring 32 rearwardly and releases it from the lock finger slot 31 which allows the standard 28 to be moved opposite any of the cartons and the same operated as described. At the same time the spring 42 engages the key 35 in its notch 36 and it cannot be withdrawn. When it is desired to withdraw the key the standard 28 is moved toward it and the lock finger 30 presses the spring 42 out of engagement with the key which is then withdrawn and the spring 32 engages the lock 30 in its slot 31, which prevents the standard from being moved and none of the records can then be withdrawn. The object of the entire mechanism and device is to lock all records but one, allowing only one to be removed at a time, 70 or to lock them all so none can be removed. It is intended that one carton shall be filled at a time, the others being moved into position in sequence when filling the case. A convenient instrument may be inserted to 75 depress the lever 19 for unfilled cartons, when the case is to be filled.

The case may be made with mechanism for a small number of cartons as illustrated. It can then be conveniently handled in the 100 manner of a filing case. The device, however, may be extended in the same form to occupy a shelf or other receptacle of desired length, and a larger number of records filed therein. The first form is adapted to household use and the second form for 105 commercial purposes.

I claim—

1. In a device of the character described, the combination of a case, a series of cartons pivoted at their lower parts in the case and in vertical position, a bell crank lever pivoted at its angle upon the case bottom opposite each carton, the lower arm of said lever being longitudinally grooved in its 110 upper part and extending within the carton, the upper lever arm having an angled member, and a thin arm secured at one end upon the rear part of the carton and extending downwardly therefrom, said arm having a 115 curved opening with a series of notches in the upper edge thereof, said opening and notches being formed and arranged to receive the lever angled member through them and the notched parts to engage said member, substantially as described.

2. In a device of the character described, the combination of a case having a transverse groove in the forward part of its bottom, a series of cartons pivoted at their 130

- lower parts in the case and in vertical position, said cartons having plates secured to their forward ends, the cartons and plates having slots therein of desired form and 5 position, guides secured along said case groove, a vertical forked standard, having means to retain it within and being slideable along said guides, strap guides secured upon the opposing case walls opposite the 10 travel path of said standard, and a lock strap passing through the strap guides and the case groove, the ends of the strap being secured upon the respective opposing forked ends of the standard in a manner to allow 15 the strap to pass through the carton slots and engage the cartons when the same are on either side of the standard, substantially as described.
3. In a device of the character described, 20 the combination of a case having a transverse groove in the forward part of its bottom, and a key opening through the front of the case at one side, a series of cartons pivoted at their lower parts in the case and 25 in vertical position, said cartons having plates secured to their forward ends, the cartons and plates having slots therein of desired form and position, guides secured along said case groove, a vertical forked 30 standard, having means to retain it within and being slideable along said guides, also having a lock finger secured upon its lower end and slotted in one side, strap guides secured upon the opposing case walls oppo- 35 site the travel path of said standard, a lock strap passing through the strap guides and the case groove, the ends of the strap being secured upon the respective opposing forked ends of the standard in a manner to allow 40 the strap to pass through the carton slots and engage the cartons when the same are on either side of the standard, a yoke spring secured at one end upon the case bottom, its opposite end extending within the case slot 45 beyond the end of the opposing guide and in a position where it can engage the said lock finger in its groove, when opposite thereto, a key having a slot in its side and adapted to pass within the key opening and 50 engage the yoke spring to press it out of engagement with the lock finger, and a spring secured at its upper end at one side of the case, its opposite end extending downward into the case groove in position to engage 55 the key in its slot, also to be engaged by the lock finger below the key to press it out of engagement therewith, substantially as described.
4. In a device of the character described, 60 the combination of a case, a series of cartons pivoted at their lower parts in the case and in vertical position, a bell crank lever pivoted at its angle upon the case bottom opposite each carton, the lower arm of said lever being longitudinally grooved in its upper part and extending within the carton, the upper lever arm having an angled member, means to cause the said lower lever arm automatically to rise and the upper lever arm to move rearwardly when the lever is 65 disengaged, and a thin arm secured at one end upon the rear part of the carton and extending downwardly therefrom, said arm having a curved opening with a series of notches in the upper edge thereof, said opening and notches being formed and arranged to receive the lever angled member through them and the notched parts to engage said member, substantially as described.
5. In a device of the character described, 80 the combination of a case having a transverse groove in the forward part of its bottom, a series of cartons pivoted at their lower parts in the case and in vertical position, said cartons having plates secured to 85 their forward ends, the cartons and plates having slots therein of desired form and position, guides secured along said case groove, a vertical forked standard, having means to retain it within and being slideable along 90 said guides, strap guides secured upon the opposing case walls opposite the travel path of said standard, a lock strap passing through the strap guides and the case groove, the ends of the strap being secured 95 upon the respective opposing forked ends of the standard in a manner to allow the strap to pass through the carton slots and engage the cartons when the same are on either side of the standard, and a bell crank 100 lever pivoted at its angle upon the case bottom opposite each carton, the lower arm of said lever being longitudinally grooved in its upper part and extending within the carton, the upper lever arm having an angled member, a thin arm secured at one end upon the rear part of the carton and extending downwardly therefrom, said arm having a curved opening with a series of notches in the upper edge thereof, said opening 105 and notches being formed and arranged to receive the lever angled member through them and the notched parts to engage said member, substantially as described.

FRANKLIN HALE CALL.
